UNITED STATES PATENT OFFICE.

CHARLES A. RICHARDS, OF CHICAGO, ILLINOIS.

MULTICOLOR-PRINTING PRESS.

1,417,769.

Specification of Letters Patent. Patented May 30, 1922.

Application filed May 27, 1921. Serial No. 472,955.

To all whom it may concern:

Be it known that I, CHARLES A. RICHARDS, a citizen of the United States, residing at Chicago, in the county of Cook and State of Illinois, have invented certain new and useful Improvements in Multicolor-Printing Presses, of which the following is a specification.

This invention relates to multi-color printing presses.

It will be explained as applied to a "cylinder" printing press although it may be employed in other types of presses.

One of the objects of this invention is to provide an improved multi-color printing press.

Another object is to provide a press in which a large number of different colors may be printed with one impression.

Another object is to provide a press in which there is no interference, overlapping or displacement of the multi-colored impressions.

Another object is to provide an improved multi-color cylinder printing press.

Another object is to provide a press wherein the multi-color attachments may be removed as units.

Other objects and advantages will herein-after appear.

An embodiment of the invention is illustrated in the accompanying drawings.

The views in the drawings are as follows:

Fig. 1 is a side elevation of a cylinder multi-color printing press, part of the press which is old and well known being omitted.

Fig. 2 is an enlarged side elevation of the ink distributing portion of the press.

Fig. 3 is a section on the line 3-3 of Fig. 1.

Fig. 4 is a section on the line 4-4 of Fig. 3.

Fig. 5 is an enlarged view of a part of the section shown in Fig. 3.

Fig. 6 is an enlarged top plan of the ductor rollers of the ink distributing system.

Fig. 7 is a section on the line 7-7 of Fig. 6.

Fig. 8 is an enlarged section on the line 8-8 of Fig. 1.

Fig. 9 is an enlarged section on the line 9-9 of Fig. 1.

Fig. 10 is a section on the line 10-10 of Fig. 9.

Fig. 11 is an enlarged side elevation of the control mechanism.

Fig. 12 is a section on the line 12-12 of Fig. 11.

Fig. 13 is an enlarged top plan of one of the ink fountains.

Fig. 14 is a section on the line 14-14 of Fig. 13.

Fig. 15 is an enlarged top plan of the selecting mechanism on one side of the press, showing one of the many selective combinations which may be set up.

Fig. 16 is an end elevation thereof.

Fig. 17 is a diagrammatic top plan of a section of a printing form arranged to be selectively inked by the arrangement of mechanism shown in Figs. 15 and 16.

Fig. 18 is a broken perspective of a typical selecting cam track section, and

Fig. 19 is a broken perspective of the type frame, showing the arrangement of the form chase and the selecting cam tracks.

The printing press comprises, in general, a flat reciprocating bed carrying the set up form to be printed; a cylindrical platen for carrying the paper or other material to and pressing the same against the form, an ink distributing system for conveying the colored inks from the ink fountains to the forms and a selecting system for selectively transferring the inks from the ink distributing system to the forms.

The bed.

The reciprocating bed or type frame 1 is the same as that ordinarily employed in cylinder printing presses. It is not illustrated in detail since various forms are well known.

In general it comprises a substantially rectangular frame work of metal which supports and to which the form chase may be secured. The bed is reciprocated back and forth so that it applies the forms in the chase first to the ink distributing system and next to the material on the revolving platen. Thus the ink is conveyed to the form and from the form to the paper or other material being printed. Various well known arrangements may be used for reciprocating the bed.

The platen.

The platen 2 is also well known in various forms. In general, it comprises a rotatable cylinder 2 which carries the paper or other

material from a hopper 3, or other suitable feeding mechanism, over and against the forms in the chase on the bed, when the same is beneath the platen, and then to suitable 5 conveyors or other delivery mechanism 4.

Ink distributing system.

The ink distributing system comprises, in general, a plurality of sets of ink storing 10 fountains A, reciprocating ductor rollers B for conveying ink from the fountains, longitudinally oscillating vibrator rollers C which receive ink from the ductor rollers, sets of intermediate rollers D which receive 15 ink from the vibrator rollers, and reciprocating form rollers E which transfer the inks from the intermediate rollers to the forms in the chase on the type frame.

Fountains.—The fountains A are the receptacles in which the vari-colored inks are retained and from which the inks are fed to the rollers. The fountains are arranged in sets transversely of the press and are adapted for individual or set adjustment, placement and removal. Each fountain is adapted to contain ink of a different color or shade from the rest so that the maximum number of colors capable of being printed on a given press at one impression is dependent upon 25 the number of fountains the press can accommodate. A press can print, at one impression, from one color up to the maximum number of colors represented by the maximum number of fountains.

30 In the press illustrated there are six sets of fountains and each set is equipped with sixteen individual fountains. Consequently the press illustrated, as it is shown equipped, can print a maximum of ninety-six different shades and colors. Of course the fountains may be made wider or narrower as desired and consequently the number of fountains per set may be varied to suit the conditions of the work to be done. Some fountains may be wide and others narrow and many other adjustments may be made so 40 that the character and variety of work which can be done is varied and great. The width of colors also may be increased by setting two or more adjacent fountains together and supplying them with the same color of ink. If this is done the inks of the same color 45 may be blended together by regulating the amount of axial movement of the vibrator 50 rollers, as hereinafter described.

Since the individual fountains and sets are alike only one need be described.

Each fountain comprises a somewhat triangular shaped hopper or compartment having side walls 5 and 6 (Figs. 13 and 14), an end wall 7 and a sloping adjustable bottom 8. The front of the hopper is open between front wall 7 and bottom 8 and this opening is closed to a more or less extent by a rotatable 65 metallic fountain roller 9, which fits

between side walls 5 and 6. The bottom of the hopper is made of suitable resilient metal and, by means of a pair of adjusting screws 10 and wedges 11, the amount of clearance or the space, between its lower edge and roller 9, may be varied. By these means the amount of ink delivered by each fountain may be readily controlled independently of all the rest of the fountains.

70 Each set of fountains is mounted upon a shaft 11 which passes through and is feathered to all of the fountain rollers 9 of that set. Each end of shaft 11 is journaled in a bracket 12 which fits into a diagonally disposed recess or notch in the side frames of the press. The brackets are thus held 75 against rotation but may be removed as desired. Adjustment of the set is accomplished by a cap screw 13 (Fig. 2) at each end. The rotation of the cap screws elevates or lowers 80 the respective brackets in their recesses in the side frames.

85 Each pair of brackets carries a cross bar 14 rigidly between them. The backs of the sets of fountains rest against their respective cross bars 14 and are prevented from rotating thereby. Since the fountain rollers are feathered on their respective shafts 11 the fountains may be individually adjusted longitudinally of their shafts (transversely of the press). The proper adjustment is maintained by cap screws 15 which clamp against the cross bar.

90 *Rotation of fountain rollers.*—The removal of the inks from the individual fountains and the even distribution thereof to the ductor rollers is facilitated by positively 95 rotating the fountain rollers by sets.

99 Each fountain set shaft 11 has a ratchet wheel 16 rigidly secured thereto. Journaled upon each shaft 11 is a bell crank lever 17 having a spring pressed pawl 18 pivotally connected to one arm thereof. Pawls 18 co-operate with the teeth of their respective ratchet wheels 16 to rotate the same. The 105 lower arms of bell crank levers 17 are provided with laterally projecting lugs 19 which fit into sockets in an oscillating bar 20. Bar 20 is pivotally carried near its opposite ends by a pair of rocker arms 21. 110 Bar 20 has a link 22 connected thereto. The other end of link 22 is connected to one arm of a bell crank lever 23 which is pivotally carried by the press side frame. The other 115 arm of bell crank lever 23 has a hole therein 24 and through this hole a rod or link 24 extends. Rod 24 has its upper end threaded 120 to receive a nut 25. A collar or stop 26 is adjustably secured to rod 24 and between collar 26 and the lower arm of lever 23 is 125 a coil spring 27. The lower end of rod 24 is pivotally connected to one of a pair of similar cams 28. Cams 28 are keyed to a shaft 29 which is rotated in the direction 130 of the arrow by a pair of gear wheels.

and 31. Gear wheel 31 is driven by a gear wheel 32 which is keyed to a shaft 33. Shaft 33 is driven from the source of power of the press through gear wheels 34, 35, 36 and 37.

When the press is in operation shaft 29 is rotated by the gear train 31, 32, 34, 35, 36 and 37, and rod 24 is reciprocated. The downward movement of rod 24 causes nut 25 to rotate bell crank lever 23 in an anti-clockwise direction forcing link 22 and bar 20 to the left (Fig. 1). This movement of bar 20 rotates all of the bell crank levers 17 in a clockwise direction and the pawls 18 carried thereby engage the teeth of their respective ratchet wheels 16 and the fountain set shafts and consequently all of the fountain rollers are rotated a slight amount. The upward movement of rod 24 tends to move nut 25 away from lever 23 but the force of spring 27 rotates the lever in the reverse direction. This reverse movement moves bar 20 to the right and all of the levers 17 are rocked in a counter clockwise direction carrying their respective pawls idly over the teeth of their ratchet wheels.

Thus while the press is in operation the ink fountain rollers are intermittently rotated always in the same direction to remove a small quantity of ink from the fountains and convey the same to the ductor rollers. The amount the fountain rollers are rotated at each step may be regulated by the position of nut 26.

35 This intermittent operation of the fountain rollers may be stopped while the press is in operation as will be hereinafter described.

Ductor rollers.—Each set of fountains has 40 a corresponding ductor roller B. The ductor rollers are preferably made of composition which is well known in the art.

The ductor rollers are carried together by a ductor frame, shown in detail in Figs. 6 and 7. The ductor frame has two side bars 40 and 41 rigidly inter-connected by cross rods 42 and 43. The side bars have corresponding pairs or sets of brackets 44 and 45 pivotally connected thereto. Each pair of 50 brackets has a shaft 46 journaled at its opposite ends therein and upon these shafts are the ductor rollers. The pivoted brackets allow the ductor rollers to individually rise when they come in contact with their corresponding vibrator rollers, thus insuring a good contact therebetween. The rollers are prevented from dropping or swinging around with their brackets by stops 47 which form abutments for cap screws 48

60 carried by the brackets. The adjustment allowed by the cap screws makes it possible to readily govern the pressure between the ductor rollers and the fountain and vibrator rollers by regulating the distance the ductor 65 rollers and their brackets can rotate.

Rollers 49 are carried by each side bar on the outside thereof. These rollers lie upon a pair of tracks 50 and 51 which are formed by the side members of the ductor cradle or carriage.

The side members of the ductor cradle may be made of angle iron as shown and are braced and held together at one end by a bar 52. The ductor frame and its rollers may be removed and replaced as a unit by 70 rolling the same in and out of the cradle on rollers 49 and tracks 50 and 51. The tracks are provided with notches 53 in which rollers 49 rest when the frame is in operating position within the cradle.

The ductor frame is locked in the cradle by a pair of sliding bolts 54 which may be projected into and removed from holes in the side members of the cradle. These bolts are operated by a pair of links 55 secured 80 thereto and to an operating handle 56 which is pivotally connected to a bracket 57 carried by cross bar 43.

The ductor cradle is oscillated so that the ductor rollers carried thereby are alternately 90 brought into contact with the fountain rollers and the vibrator rollers. The cradle is carried by two pairs of links 58 and 59, one link of each pair being pivoted to opposite side frames of the press. Links 58 are journaled at one end near the opposite ends of bars 52. Bar 52 has a pair of connecting rods 60 pivotally connected to its opposite ends. The lower ends of rods 60 are pivoted to levers 61 through adjustable elbows 62. 100 Levers 61 each carry a cam roller 63, which bear upon the surfaces of cams 28.

Consequently when cams 28 are rotated through gear train 37, 36, 35, 34, 32, 31 and 30 in the operation of the press as hereinbefore described the ductor cradle, ductor frame and rollers are alternately moved into the position shown by the full lines of Fig. 4 where the ductor rollers engage the fountain rollers and the position shown by the 110 dotted lines where the ductor rollers engage the vibrator rollers C.

Vibrator rollers.—Each set of fountains has a corresponding vibrator roller C. The vibrator rollers are preferably made of steel 115 and are in sections, each section corresponding to a fountain in the corresponding set.

The vibrator rollers are carried together in a frame and may be inserted and removed as a unit.

Fig. 8 shows the vibrator rollers in greatest detail.

The sections of each vibrator roller are adjustably but rigidly secured to a shaft 70 by set screws 71. Shafts 70 are journaled 125 at their opposite ends in side frames 72 and 73 of the vibrator frame. The frame is strengthened and held together by bars 74 and 75 at opposite ends thereof. Adjacent vibrator roller sections may be brought to 130

gether in the same way that the fountains can be brought together when the width of the colors is to be increased.

The side frames 72 and 73 are provided 5 with rollers 76 which support the vibrator frame upon the tops of the webs of T-iron 77. One of the T-irons extends along and is secured to each side frame of the press. The top of the web of each iron 77 is provided 10 with notches or depressions 78 into which the respective rollers 76 lie when the frame is in proper operative position. The tops of the webs of irons 77 form tracks over which the vibrator frame may be moved into 15 and out of operative position on rollers 76. When the frame is moved in, rollers 76 are upon the elevated sections of the tracks and the vibrator rollers are held above the upper sets of intermediate inking rollers D. As 20 the frame approaches operative position rollers 76 pass down the inclined surfaces of the notches in their tracks bringing the vibrator rollers in proper relation to the intermediate inking rollers. The frame may 25 be readily pulled out for the inspection, cleaning and removal of the vibrator rollers. The frame is locked in position in the press frame by a pair of sliding bolts 79 which cooperate with sockets in the press side 30 frames. The bolts are slidably mounted on brackets 80 carried by rod 75 and are actuated by links and a handle as hereinbefore explained in connection with the ductor frame.

35 Rotation of vibrator rollers.—To improve the distribution of ink the vibrator rollers are positively rotated.

Each vibrator roller shaft has a pinion 81 rigidly secured thereto. These pinions in 40 pairs engage pinions 82 carried by shafts 83 journaled in side frame 72 of the vibrator frame. The end of each shaft 83 is provided with the tongued member of a coupling 84. The grooved members of couplings 84 are 45 carried by stud shafts 85 slidably journaled in the side frame of the press. The stud shafts are slidably journaled so that they may be moved in and out to connect and disconnect couplings 84. Each shaft 85 has a 50 pinion 86 rigidly secured thereto. Pinions 86 are driven by gear wheel 36 through suitable gear trains shown in outline in Fig. 1.

When the vibrator frame is pulled out of 55 operative position the couplings 84 are separated by moving shafts 85 axially, and when the frame is moved to operative position the couplings are readily engaged to provide the drive for the vibrator rollers.

50 Vibration of vibrator rollers.—To further 60 improve the uniform distribution of ink the vibrator rollers are reciprocated axially or transversely of the press.

A pinion 90 is secured to a stud shaft journaled to the press frame. Pinion 90

has a connecting rod 91 eccentrically connected thereto. The upper end of rod 91 is connected to one arm of a bell crank lever 92, the other arm of which is connected to a link 93. Link 93 is connected to a link 94. Link 94 is carried by 70 and pivotally connected to three double bell crank levers 95. Levers 95 are pivotally secured to the press side frame by pivot screws 96. The two free ends of each lever 95 are provided with rollers 97 which, when the 75 vibrator frame is in position, lie between collars 98 secured to vibrator roller shafts 70. Each lever is associated with two vibrator rollers.

When the press is in operation the rotation of gear wheel 32 reciprocates connecting rod 91 and consequently link 94. The reciprocation of link 94 oscillates levers 95 each of which alternately moves in and out the two vibrator rollers associated therewith.

The extent of movement or vibration may be regulated by an adjustable connection 99 between connecting rod 91 and pinion 90. The pinion is radially slotted and, by changing the position of the pin which interconnects the pinion and connecting rod, the eccentricity, and consequently the amount of reciprocation, may be varied.

As previously described the vibrator 95 rollers are engaged by the ductor rollers, when the same are depressed, and remove ink therefrom. The axial movement between the positively driven and vibrated 100 vibrator rollers and the ductor rollers insures a more uniform distribution of ink. The ink is transferred by the vibrator rollers to the intermediate rollers D.

Intermediate rollers.—There may be as many duplicate sets of intermediate rollers 105 as are required to give the necessary uniformity of ink distribution so that a thin, evenly distributed film of ink is transferred to the form rollers. Two such sets of intermediate rollers have been found to give 110 excellent results and two sets are illustrated.

The upper set of distributor rollers, which may be called rider rollers, are composed of composition and there is one roller for each set of fountains. The rider rollers are on 115 shafts 105 and are not positively driven. Shafts 105 are journaled at opposite ends in side members 106 of a rider roller frame. The rider frame is supported upon the inside flanges of T irons 77 through rollers 107. 120 The inside flanges of the T irons are provided with small notches or depressions in which rollers 107 lie when the rider frame is in operative position. The rider frame and the rider rollers carried thereby may be moved into and out of operative position 125 and removed and inserted into the press as a unit. The frame may be locked in posi-

tion by means of latch bolts as in the case of the ductor and vibrator frames.

The lower set of intermediate rollers D, which for convenience may be termed distributor rollers, are preferably composed of metal. It may, if desired, be sectioned to correspond to the fountains in each set, although ordinarily this is not necessary and it is not shown. There is one distributor 10 roller for each set of fountains.

Each distributor roller is carried by a shaft 108. Shafts 108 are journaled in the side members 109 of the distributor frame. This frame, which is similar to those previously described, is suspended from the outside flanges of T irons 77. The side members each have three brackets 110 carrying rollers 111 which ride upon the outer flanges. The outer flanges may be without 20 depressions allowing the distributor frame to move and lie in the same plane.

The distributor rollers are positively rotated during the operation of the press. Each shaft 108 has a pinion 112 secured thereto. These pinions are engaged in pairs by pinions carried on shafts which are journaled in the distributor frame and carry the tongued member of a detachable coupling 113. This arrangement is similar to the 30 drive for the vibrator rollers clearly shown in Fig. 8. The grooved members of couplings 113 are carried on axially movable shafts 114 each of which has a pinion 115 secured thereto. The three pinions 105 are 35 driven by gear wheel 36 through suitable gear trains shown in outline in Fig. 1.

The distributor rollers remove ink from the corresponding rider rollers and transfer the same to the form rollers E.

40 *Form rollers.*—The form rollers are preferably made of composition and there is one roller for each set of fountains.

Figs. 9 and 10 show the form rollers in greatest detail.

45 Each form roller is carried by a shaft 120 which is journaled at opposite ends in brackets 121. Brackets 121 are pivotally carried by side members 122 of a form roller frame. The form roller frame is held together and 50 braced at its ends by rods 123 and 124. Brackets 121 are biased downwardly against stops 125 by springs 126. Adjusting screws 127 serve to individually regulate the amount the springs can depress their respective brackets and form roller shafts at each end.

Each side member 122 of the form roller frame is provided with three supporting rollers 128. Rollers 128 rest upon side frame 60 tracks 129 of a form roller cradle 130.

Form roller cradle 130 is pivotally carried on the side frames of the press by a pair of pivoted brackets 131 on each side of the cradle. The form roller cradle is rocked

upon brackets 131 to bring the form rollers 65 alternately into contact with the distributor rollers and into a position to ink the forms as will be hereinafter described.

Pivots connected to the opposite side frames of the form roller carriage are a pair 70 of adjustable connecting rods 132. Connecting rods 132 are loosely fitted upon shaft 33 so as to be capable of radial oscillation with respect thereto. Rods 132 each carry a cam roller 134 adapted to ride upon a cam 75 135 which is rigidly secured to shaft 33. When shaft 33 is rotated, as previously described, the cooperation of cam 135 and roller 134 causes the connecting rod to reciprocate rocking the form roller carriage and 80 form rollers upon brackets 131. The downward movement is arrested by adjustable stop screws 136 which engage projecting lugs on the press frame.

When the form rollers are in their lowermost position they are in condition to selectively ink the form in accordance with a prearranged color combination.

Color selection.—Type frame 1, in which the set up chase of forms is secured, has an 90 elevated ledge 140 along each longitudinal edge thereof. In the channel between ledges 140 the chase and selecting blocks are secured.

The selecting blocks, one of which is adjacent the inner edge of each ledge 140, comprises a channeled or grooved metal block 141. Each block 140 is provided with a series of parallel longitudinal tapering walled grooves or channels 142. These channels are for receiving and holding taper headed nuts 143 which cooperate with screws 144 (See Fig. 18) to hold cam track sections 145 to the selecting blocks. The grooves allow the track sections to be moved along the selecting blocks, providing for a 105 ready adjustment of the press to print different combinations, sizes, and arrangements of color impressions.

The track sections 145 are metal bars provided with beveled or sloping ends (see 110 particularly Figs. 18 and 19). Placing these bars end to end in the grooves of the selecting block provide a series of notched tracks. The location and length of the raised and depressed portions of the tracks formed by 115 sections 145 may be varied as desired by changing the lengths and separation of the sections. The length of an elevated section may be made readily adjustable by providing track sections 145 with complementary 120 offset ends 146.

In the press illustrated there are six longitudinal grooves in each selecting block, corresponding to the number of sets of fountains. There are consequently two parallel notched selecting tracks for each fountain set or for each form roller.

Each form roller shaft 120 is provided at

each end with a roller 147. Rollers 147 are adapted to ride upon the type frame ledges 140 and sustain the weight of the form rollers when the same are in inking position 5 as will be hereinafter described.

Each form roller shaft is also provided with an axially adjustable selecting roller 148 at each end. Rollers 148 of the respective form rollers are adapted to align with 10 one of the longitudinal grooves of each selecting block so as to ride upon the elevated portions of the corresponding track sections when the form roller cradle is depressed as hereinbefore described.

15 When the type frame moves beneath the form rollers in the direction of the platen, the form roller cradle is depressed. Consequently the form rollers, due to the cooperation of their selecting rollers and the cam 20 tracks, are held in an elevated position until the depressions in the tracks are reached, whereupon the corresponding form roller is allowed to drop and remain depressed. The roller remains depressed, supported in inking 25 relation to its corresponding transverse row of forms by rollers 147, until an elevated section of track is again reached. When the elevated section is reached the form roller is again raised by the elevated 30 track sections so that it can not engage the other form sets in the chase. When the form rollers are depressed, by their selecting rollers being in one of the track depressions, the rollers will engage and ink any forms 35 which may be directly beneath. By this arrangement the contact between transverse rows of forms and the form rollers is selectively controlled so that the colors carried by any particular form roller are applied 40 only to the desired printing form set in the chase.

In order to print a particular grouping of colors the forms are set and locked in the chase and the selecting track sections are 45 adjusted so that when the type frame moves beneath the depressed form roller cradle the form rollers are held above the transverse rows or sets of forms which are not to receive their colors but are allowed to drop and ink 50 those transverse rows of forms which should receive their colors. Each form roller has a band or strip of color corresponding to each fountain in the corresponding set. These colors are maintained separate and distinct 55 throughout all of the ink distributing system. No roller, whether it be ductor, vibrator, rider, distributor, or form has more than one color around its circumference although each may have as many colors side by side 60 as there are fountains in the corresponding set. Thus, in the press illustrated as it is equipped, each roller has sixteen different shades or colors throughout its length.

Figs. 15, 16, 17 and 19 show a typical "set 65 up" for color selective printing. The indi-

vidual form rollers and corresponding transverse rows or sets of forms are designated I, II, III, . . . VI in the order in which they come into ink transferring relation. The track depressions which allow 70 the ink transferring contact between the form rollers and transverse sets of individual forms are similarly designated. In the illustrated combination each form roller contacts two transverse rows of forms 75 providing for the double or duplicate reproduction of all of the colors.

Thus as the type frame moves in the direction of the arrow toward the platen, form roller I, whose selecting rollers 148 first meet 80 the right hand depression I, inks the right hand transverse row of forms I. The other form rollers are held above row I of forms because their selecting rollers 148 are on elevated cam track sections. Upon the continuance of the travel of the type frame, form roller I is lifted after it has inked the transverse row I of forms and when depression II is reached form roller II is depressed 85 to ink transverse row II. All of the other 90 form rollers are held elevated. Next form roller III cooperating with depression III inks form row III and so on until all six of the form rollers have inked their corresponding rows or sets of forms. In the "set 95 up" shown after one complete cycle of inking is completed the operations are duplicated and the second group of forms I to VI, inclusive, are inked in a similar manner.

Control mechanism.—The removal of ink 100 from the fountains and the inking of the forms may be stopped and started without interrupting the operation of the printing press.

This control is accomplished by stopping 105 and starting the rotation of the fountain rollers and the oscillation of the form roller cradle.

Figs. 11 and 12 show the details of the 110 control mechanism.

Pivoted to the press frame is a foot lever 150 whose shaft 151 has a pair of levers 152 secured thereto. Each lever 152 has a block 153 at its free end. A pair of trip rods 154 and 155 slidably fit in openings in one block 115 153 while the block of the other lever has an opening only for a rod 154.

Rods 154 are each provided with adjusting nuts 156 and, between nuts 156 and block 153, is encircled by a coil spring 157. Each rod 154 is connected to an arm 158 projecting from a collar 159 which is freely carried by shaft 33. The rotation of shaft 33 does not move collars 159 but these collars may be oscillated independently of the 120 rotation of the shaft by their arms 158. Collars 159 each carry a curved arm 160 whose outer end carries a cam 161. Cams 161 125 cooperate with cam rollers 134 to lift the same from operative relation to cams 135, and 130

thus control the oscillations of the form roller cradle.

Rod 155 is provided with similar adjusting nuts 162 and a spring 163. The other 5 end of rod 155 is connected to a lever 164 which is pivotally secured to the press side frame on a pivot pin 165. The upper end of lever 164 is formed into a hook 166 which is adapted to engage and hold one arm of lever 23 and thus arrest the oscillation of bar 20 and the fountain roller pawls.

When it is desired to stop the fountain rollers and the oscillations of the form roller cradle without stopping the entire press, the 15 operator depresses treadle 150. The depression of treadle 150 rocks levers 152, which through springs 157 and 163, moves both of the trip rods 154 and trip rod 155. Rods 154 rotate collars 159 and cams 161 lifting 20 rollers 134 clear of cams 135. The oscillation of the form roller cradle is thereby stopped. At the same time the oscillation of levers 152 draws back trip rod 155 rocking lever 164 in a clockwise direction (Fig. 25 11) about its pivot 165 and moving hook 166 into a position to interlock with lever 23 of the fountain roller operating system. On the next depression of the arm of lever 23 hook 166 interlocks with the same and, 30 since the lever is thus prevented from returning, the fountain roller pawls are stopped.

Summary of operation.

35 Briefly summarized, the operation of the press is as follows:

The vari-colored inks are placed in the fountains and arranged individually and in sets corresponding to the desired arrangement of impressions. The forms are set up 40 in the chase and the cam track sections are adjusted so that the form rollers will engage the proper sets or transverse rows of forms and be held from engagement with all the 45 other sets. The forms are locked in the chase in any approved manner.

When power is turned onto the press the type carriage reciprocates as is usual in cylinder presses, moving alternately beneath 50 the form rollers to ink the forms and beneath the platen to transfer the inks to the paper or other material thereon. The ink fountain rollers are intermittently rotated, always in the same direction, to remove the 55 inks from the fountains. The ductor roller cradle oscillates up and down bringing the ductor rollers alternately into contact with the fountain rollers and the vibrator rollers.

The cams operating the fountain rollers 60 and oscillating the ductor cradle are so related that the fountain rollers are rotated while they are in contact with the ductor rollers. Thus each set of fountain rollers transfers to the corresponding ductor roller 65 a set of colors corresponding to the colored

inks in the fountains. The rolling contact between the fountain and ductor rollers insures an even distribution of ink.

When the ductor rollers are down, due to the depression of the ductor cradle, the 70 inks on each set thereof are transferred to the corresponding vibrator roller. The positive drive and vibration of the vibrator rollers cause a rolling and sliding contact between the ductor and vibrator rollers effecting a uniform transfer of inks therebetween.

75 The vibrator rollers transfer the inks to the corresponding rider rollers, which in turn transfer the same to the distributor rollers.

80 The distributor rollers pass the inks to the corresponding form rollers when the form roller cradle is up bringing the corresponding rollers into contact.

85 While the form rollers are up taking ink from the distributor rollers the type frame moves back under the form roller cradle and then starts forward toward the platen. Before the forms come beneath the form rollers in this forward movement the form 90 roller cradle is down in operative relation to the cam tracks carried by the type frame. The type frame passes along under the form rollers which are selectively brought into contact with the proper sets of forms inking the same. The type frame then passes beneath the platen and the forms are pressed against the paper or other material carried thereby. After the impressions are made the paper is delivered from the platen, the type 100 carriage returns to again ink the forms and the cycle of operations is repeated.

95 The inks in each set or transverse row of colors is maintained independent and separate from the inks of other sets. No roller 105 carries more than one color circumferentially and, since the transverse separation of colors is not at all difficult, there is no tendency to mix or overlap the colors.

Having described my invention what I 110 claim as new and desire to secure by Letters Patent, is:—

1. A multi-color printing press having a plurality of sets of ink fountains, a platen, a form roller for each set of fountains, intermediate rollers for transferring ink between each set of fountains and a corresponding form roller, a reciprocatory type frame for carrying the forms between the form rollers and the platen, and means for selectively bringing the form rollers into contact with forms on the type frame.

115 2. A multi-color printing press having a platen; a plurality of sets of ink fountains, each set containing a plurality of independent individual fountains; a form roller for each set of fountains; intermediate rollers for transferring ink from the fountains to the form rollers; a reciprocatory type frame for holding a chase of printing forms and 120 125 130

carrying the same alternately to the form rollers and the platen; and selecting means for selectively producing ink transferring contact between the form rollers and the forms in the chase.

3. A multi-color printing press having a rotatable platen, a series of ink fountains arranged in sets, a reciprocatory type frame carrying printing forms in sets corresponding to the sets of fountains, a plurality of selectively operable form rollers one for each set of fountains, a series of rollers individual to each set of fountains and transferring the inks therefrom to the corresponding form roller, and selecting means associated with the form rollers and the type frame for selectively bringing the respective form rollers into contact with corresponding sets of forms.

10 4. A multi-color printing press having a platen, a series of ink fountains arranged in sets, a reciprocatory type frame for carrying printing forms arranged in sets corresponding to the sets of fountains, a plurality of intermediate rollers for transferring ink from the fountains, a plurality of individually selectable form rollers which are oscillated together alternately in a position to engage the intermediate rollers and the forms in 15 the type frame, and means for selectively bringing the form rollers into contact with corresponding sets of forms.

5. A multi-color printing press having a platen, a reciprocatory type frame for holding a plurality of sets of printing forms and carrying the same alternately into inking position and into printing position relative to the platen, a plurality of inking fountains arranged in sets corresponding to the sets 20 of forms, a form roller for each set of fountains and transferring the ink supplied thereby to the forms, and selecting means for selectively causing the form rollers to contact with the printing forms on the frame before 25 the same moves to printing position.

6. A multi-color printing press having a plurality of sets of ink fountains, each having a rotatable fountain roller for transferring the ink therefrom, an oscillating form roller cradle, a plurality of form rollers carried by the cradle and individually movable with respect thereto, a platen, a reciprocatory type frame for carrying a plurality of printing forms arranged in sets corresponding to the fountain sets, selecting means 30 associated with the type frame and the individual form rollers for selectively causing the form rollers to contact the forms, and means for controlling the rotation of the 35 fountain rollers and the oscillations of the form roller cradle independently of the rest of the press.

7. A multi-color printing press having a rotatable cylindrical platen, a plurality of inking fountains arranged in sets, a form

roller for each set of fountains, an independent series of ink distributing rollers between each set of fountains and a corresponding form roller, a reciprocating type frame for holding printing forms in sets 70 corresponding to the fountains and movable to the form rollers for obtaining ink and to the platen for printing impressions, and selecting means for causing certain form rollers to engage certain sets of forms. 75

8. A multi-color printing press having a rotatable platen, a plurality of form rollers, a reciprocatory type frame for holding a chase in which printing forms may be arranged in sets corresponding to the form 80 rollers and movable to the form rollers to ink the forms and to the platen to apply ink from the forms, a plurality of individually adjustable ink fountains capable of being arranged in sets corresponding to the form 85 rollers, one set for each form roller, a series of ink distributing rollers individual to each form roller and corresponding set of fountains and acting to convey the inks from the fountain sets to corresponding form rollers, 90 and selecting means to cause the form rollers to selectively engage sets of forms when the type frame is moved to ink receiving position.

9. A multi-color printing press having a 95 platen, a group of form rollers, a reciprocatory type frame on which printing forms may be arranged in sets corresponding to the form rollers and movable to inking position relative to the form rollers and printing position relative to the platen, selecting means including adjustable cam tracks mounted on the type frame and acting to bring certain form rollers in contact with certain sets of forms and prevent contact 100 with other sets of forms when the type frame is moved to inking position, a series of sets of ink fountains, one set for each form roller, and ink distributing rollers between each set of fountains and corresponding form roller. 110

10. A multi-color printing press having ink fountains for arrangement in sets; a plurality of groups of ink distributing rollers, each group including a roller for each set of fountains; an independently removable frame for carrying each group of ink distributing rollers; a platen; a fountain roller for each set of fountains and to which inks are transferred by the distributing rollers; a type frame movable between the form rollers 115 and the platen and on which forms may be arranged in sets corresponding to the fountain sets; and means for causing selective contact between forms and form rollers. 120

11. A multi-color printing press having a 125 series of ink distributing rollers, sets of ink fountains, a form roller for each set of fountains, a reciprocatory frame for carrying the form rollers to and from the ink distributing rollers, a reciprocatory type frame on 130

which forms may be arranged in corresponding sets and movable to the form rollers, adjustable selecting rollers for each form roller, and adjustable cam tracks carried by the type frame, the selecting rollers and cam tracks cooperating when the type frame moves to the form rollers to cause contact between some forms and form rollers and prevent contact between other forms and form rollers. In testimony whereof I hereunto subscribe my name. 10

CHARLES A. RICHARDS.
